UNITED STATES PATENT OFFICE.

LA MONT A. McDOWELL, OF DETROIT, MICHIGAN, ASSIGNOR TO HUPP MOTOR CAR CORPORATION, OF DETROIT, MICHIGAN, A CORPORATION OF VIRGINIA.

STRIKER-PLATE ASSEMBLY.

Application filed June 1, 1926. Serial No. 112,950.

This invention relates generally to striker plate assemblies and refers more particularly to those designed for use in vehicle body constructions.

5 One of the essential objects of the invention is to provide an assembly of this type in which a plurality of striker plates are held in assembled position by a common securing means.

10 Another object is to provide a strong and durable structure that is simple in construction and can be manufactured at a comparatively low cost.

15 With these and other objects in view, the invention resides in certain novel features of construction, combinations and arrangements of parts as will be more fully described and particularly pointed out in the appended claims.

20 In the accompanying drawing:

Figure 1 is a fragmentary side elevation of a door jamb embodying my invention.

Figure 2 is a fragmentary front elevation of the door jamb.

25 Figure 3 is a sectional view taken on the line 3—3 of Figure 1 and showing fragments of two doors at dotted lines.

Referring now to the drawing, 1 is a door jamb of a vehicle body of the sedan or four door type. As shown, this jamb is box like in form and comprises the upright channel member 2 and the cooperating metal strip 3. Preferably, this strip is wider than the base 4 of the channel member 2 and is embraced 30 by return-bent portions 4' of laterally extending flanges 5 at the inner edges of the channel member. Thus these flanges 5 constitute abutments for the doors 6 and 7 respectively when in closed position.

40 As shown in Figure 3, the side walls 8 and 9 respectively of the channel member are provided with transversely extending inwardly embossed or depressed portions 10 and 11 respectively which receive suitable 45 striker plates 12 and 13 respectively. In the present instance these depressed portions 10 and 11 are channel-shape in form and have curved rear walls 10' and 11' respectively that connect into the lateral flanges 5, while each striker plate is a metal casting and has 50 two integral steps 14 and 15 respectively that are adapted to be engaged by the locking bolts 17 and 18 carried by the respective doors 6 and 7. To facilitate the assembly 55 operation, the bases of these striker plates

have laterally extending lugs or projections 19 and 20 respectively that extend through aligned openings 21 and 22 in the side walls 8 and 9 respectively of the jamb. As shown in Figure 3 these lugs 19 and 20 preferably 60 abut, and are engaged by a suitable screw 23 which effectively holds the striker plates in position. Thus, a single securing element will suffice to hold the parts together. In view of this arrangement the assembly 65 operation is simplified with a material saving in time, labor and material; hence the cost of manufacturing such assemblies is correspondingly reduced.

While it is believed that from the foregoing description, the nature and advantage of my invention will be readily apparent, I desire to have it understood that I do not limit myself to what is herein shown and described and that such changes may be 70 resorted to when desired as fall within the scope of what is claimed.

What I claim as my invention is:

1. A striker plate assembly comprising a jamb having recesses in two sides thereof, 75 striker plates in said recesses, and a common securing means for said striker plates.

2. A striker plate assembly comprising a jamb including a channel member having transversely extending depressed portions in the opposite side walls thereof, striker plates in said depressed portions, and a common securing means for said striker plates.

3. A striker plate assembly comprising a jamb having inwardly depressed portions at 80 opposite sides thereof, striker plates in said depressed portions, and securing means for said striker plates including an element extending transversely of both of said striker plates.

4. A striker plate assembly comprising a jamb having aligned openings in the sides thereof, striker plates on the sides thereof having projections entering said recesses, and securing means for said striker plates 85 including an element engaging said projections.

5. A striker plate assembly comprising a jamb having a channel-shaped member provided with laterally extending flanges, the side walls of said channel-shaped member being provided with channel-shaped recesses, the inner end walls of the channel recesses connecting into the lateral flanges aforesaid, 90 striker plates in said recesses cooperating 95

with the side and inner end walls of said recesses to define latch receiving recesses.

6. A striker plate assembly comprising a jamb having depressed portions in the side walls thereof, striker plates in said depressed portions having laterally extending projections, and securing means for said striker plates comprising an element extending freely through one of said projections and 10 threadedly engaging the other of said projections.

7. A striker plate assembly comprising a jamb having openings in two sides thereof, striker plates on said sides and having lateral projections in said openings, and securing means for said striker plates including an element extending transversely of 15 said jamb and extending longitudinally of said lateral projections.

8. A striker plate assembly comprising a jamb having openings in two sides thereof, striker plates on said sides and having lateral projections in said openings, and securing means for said striker plates including an element extending freely through the lateral projection of one of said striker plates and threadedly engaging the lateral projection of the other of said striker plates. 20

9. A striker plate assembly comprising a jamb, striker plates upon two sides of said jamb, and means for securing said striker plates to said sides of said jamb, including adjustable element extending transversely of 30 said jamb and said striker plates.

In testimony whereof I affix my signature.

LA MONT A. McDOWELL.
